Inventor

J.R. Francis,

Attorney

UNITED STATES PATENT OFFICE

JACOB RICHARD FRANCIS, OF FLINT, MICHIGAN

CHARGE-HEATING CONTROL FOR INTERNAL-COMBUSTION ENGINES

Application filed September 21, 1922. Serial No. 589,552.

This invention relates to certain new and useful improvements in a charge heating control for internal combustion engines and more particularly to a baffle valve for baffling the exhaust gases passing out through the exhaust pipe, the object being to provide an automatic valve which will automatically regulate the passage of the exhaust gases to the heating chamber.

10 Another object of my invention is to provide a valve which is capable of being attached to any of the well known forms of exhausts used in connection with internal combustion engines and in connection with any 15 of the well known heating means employed for heating the charge before it is delivered to the internal combustion engine whereby the exhaust gases will be baffled so that they will be diverted to the heating chamber when the engine is running at slow intermediate speed, the valve being so weighted that when the engine is running at high speed the pressure will be sufficient to open the valve in order to allow the gases a free 25 passage therethrough.

Another object of my invention is to provide a valve which is adapted to be constructed to suit the engine to which it is attached whereby the maximum pressure of any of the 30 well known makes of engine will open the valve and allow the gases to pass therethrough and when said engine is idle or running at intermediate speed, the pressure will not be sufficient to open the valve thereby 35 causing the exhaust gases to be conveyed through the heating chamber.

Other and further objects and advantages of the invention will be hereinafter set forth and the novel features thereof defined by the 40 appended claim.

In the drawings,

Figure 1 is a side elevation or portion of an internal combustion engine showing the 45 application of my improved construction of automatic valve thereto; and

Figure 2 is a vertical section through the valve showing the valve in its normal or closed position.

50 In Figure 1 of the drawing 1 indicates an

internal combustion engine, 2 the exhaust manifold, 3 the intake manifold, 4 the carburetor and 5 a heating jacket surrounding the intake manifold above the carburetor, the above description being given so that the operation of my improved construction of automatic heat regulating valve can be readily understood.

The exhaust manifold is provided with the usual exhaust pipe 6 which extends to the 60 muffler in the usual way.

In carrying out my invention I cut the exhaust pipe and arrange between the ends thereof a valve casing 7 having an inlet 8 and an outlet 9 to which the free ends of the 65 exhaust pipe 6 are adapted to be connected in any of the well known manners as clearly shown. The valve casing 7 is provided with a bearing 10 in which the rounded pivot portion 11 of a weighted swinging valve 12 is 70 pivotally mounted. The valve is adapted to normally assume the position as shown in Figure 2 so as to close the passage through the valve casing. The valve casing is provided with a removable cover 13 which is secured 75 in position by bolts as clearly shown so as to facilitate the inserting of the valve and the removal of the same. The opposite side of the valve casing 7 is provided with an outlet nipple 14 to which is connected a flexible 80 pipe 15 which extends to the inlet of the heating chamber 5. The heating chamber is provided with an outlet having a flexible pipe 16 extending to an inlet nipple 18 in the valve casing 7 below the valve whereby the exhaust gases under normal conditions will 85 pass out through the outlet 14 through the pipe 15 into the heating chamber 5, from the heating chamber through the pipe 16 into the valve casing 7 through the nipple 18 and out through the exhaust pipe in the ordinary manner. While I have shown the particular construction of heating chamber with an inlet and outlet and a valve casing with an inlet and outlet nipple for connecting 90 the flexible pipes thereto, I do not wish to limit myself to the use of any particular construction of heating chamber or the use of the return conduit for the gases to the valve 95 as I am fully aware that in some heating

100

devices the exhaust gases after passing through the heating chamber are discharged into the atmosphere and my construction of automatic valve of course, does not depend upon returning the gases to the exhaust line as the object of my invention is to provide a swinging weighted valve which will baffle the exhaust gases discharged from the internal combustion engine when running at an intermediate speed to enable the gases to be forced through the outlet into the heating chamber.

I have found by experimenting with a Buick car for instance that when running at high speed the muffler exerts a back pressure of substantially eight pounds and by constructing the swinging weighted valve of such weight that the valve will remain closed until eight pounds pressure is exerted by the motor, the exhaust gases will be prevented from passing through the ordinary exhaust pipe line and diverted to the heating chamber so as to quickly heat the incoming charge delivered from the carbureter before it reaches the internal combustion engine.

While I have shown the particular construction of valve it is, of course, understood that I do not wish to limit myself to any particular construction of valve or valve casing as my invention consists broadly in providing the exhaust line of an internal combustion engine with a valve which baffles the outgoing gases of the internal combustion engine at intermediate speeds and opens at high speed so as to allow the gases to pass in a normal path of travel. I therefore do not wish to confine myself to any details of construction and I reserve the right to use various forms of valves in order to accomplish this purpose without departing from the spirit of my invention.

From the foregoing description it will be seen that I have provided an internal combustion engine with a heating chamber for heating the charge delivered thereto through the medium of the exhaust gases which are baffled in the exhaust gas line until the engine reaches a high speed where the weight of the baffling valve is overcome by the pressure of the engine and allows the gases to pass in a normal path of travel through the exhaust pipe.

What I claim is:

A valve of the kind described comprising a valve casing having inlet and outlets out of vertical alignment to form an elbow-shaped casing, said valve casing being provided with a cylindrical horizontally disposed bearing at the junction of the passages, a valve having a cylindrical pivot at one edge detachably mounted in said bearing and adapted to be normally held in vertical position by gravity, said valve pivot being slidably mounted within said bearing and a removable cover for said valve casing for hold-

ing said pivot within said bearing and to allow said valve to be removed therefrom.

In testimony whereof I hereunto affix my signature.

JACOB RICHARD FRANCIS.
